(57) **CLAIM**

The ornamental design for a display screen with an insurance authorization/preauthorization dashboard graphical user interface, as shown and described.

DESCRIPTION

A portion of the disclosure of this patent document may contain material to which a claim for copyright and trademark may be made. The copyright and trademark owner has no objection to the reproduction of the patent document or the patent disclosure, as it appears in the U.S. Patent Office records, but reserves all other copyright and trademark rights whatsoever.

The FIGURE is a front view of the display screen with an insurance authorization/preauthorization dashboard graphical user interface, in accordance with our new design.

The broken lines showing the display screen is provided for the purpose of illustrating portions of the article and forms no part of the claimed design.
